CLAIM

The ornamental design for a fence screen, as shown and described.

DESCRIPTION

FIG. 1 is a perspective view of a fence screen showing my new design;

FIG. 2 is a front view thereof;
FIG. 3 is a rear view thereof;
FIG. 4 is a right side view thereof;
FIG. 5 is a left side view thereof;
FIG. 6 is a top view thereof;
FIG. 7 is a bottom view thereof;
FIG. 8 is an enlarged perspective view of the left upper portion thereof;
FIG. 9 is a perspective view of a second embodiment of a fence screen showing my new design;
FIG. 10 is a front view thereof;
FIG. 11 is a rear view thereof;
FIG. 12 is a right side view thereof;
FIG. 13 is a left side view thereof;
FIG. 14 is a top view thereof;
FIG. 15 is a bottom view thereof;
FIG. 16 is an enlarged perspective view of the left upper portion thereof, shown at 2x scale of FIG. 9;
FIG. 17 is a perspective view of a third embodiment of a fence screen showing my new design;
FIG. 18 is a front view thereof;
FIG. 19 is a rear view thereof;
FIG. 20 is a right side view thereof;
FIG. 21 is a left side view thereof;
FIG. 22 is a top view thereof;
FIG. 23 is a bottom view thereof;
FIG. 24 is an enlarged perspective view of the left upper portion thereof, shown at 2x scale of FIG. 17;
FIG. 25 is a perspective view of a fourth embodiment of a fence screen showing my new design;
FIG. 26 is a front view thereof;
FIG. 27 is a rear view thereof;
FIG. 28 is a right side view thereof;
FIG. 29 is a left side view thereof;
FIG. 30 is a top view thereof;
FIG. 31 is a bottom view thereof; and,
FIG. 32 is an enlarged perspective view of the left upper portion thereof, shown at 2x scale of FIG. 25.
The broken lines along two sides of peripheral edges represent stitching and form part of the claim. The broken lines of grommets in various figures represent portions that form no part of the claimed design.

(Continued)

The drawings contain a symbolic break. The portion between the break lines forms no part of the claimed design.
